CLAIM

The ornamental design for flexible hair for a doll, as shown and described.

DESCRIPTION

FIG. 1 is a perspective view of the front and one side of flexible hair for a doll;

FIG. 2 is a front perspective view thereof, on a reduced scale;

FIG. 3 is an enlarged side perspective view, thereof;

FIG. 4 is an enlarged opposite side perspective view thereof;

FIG. 5 is an enlarged top perspective view thereof; and,

FIG. 6 is an enlarged rear perspective view, thereof.

The strands of hair are shown in alternative positions in each of the views of the drawing to indicate flexibility and the broken line showing of the doll is for illustrative purposes only and forms no part of the claimed design.
